ATTORNEY

UNITED STATES PATENT OFFICE.

MAX SCHIERS, OF GROSSENBAUM, NEAR DUSSELDORF, GERMANY.

TOBACCO PIPE.

Application filed July 8, 1920. Serial No. 394,857.

To all whom it may concern:

Be it known that I, MAX SCHIERS, a citizen of the German Republic, and residing at Grossenbaum, near Dusseldorf, Germany, 5 have invented certain new and useful Improvements in Tobacco Pipes, of which the following is a specification.

This invention relates to a tobacco pipe having a smoke chamber and a spit basin 10 and connecting channels between said spit basin and smoke chamber, said channels being easily cleaned and allowing the spit to flow out. One of these two channels is a smoke sucking channel, being suitably connected to the hollow space of the tobacco pipe bowl and leading from the smoke chamber to the spit basin and the other channel is a spit discharging channel, leading from the bottom of the smoke chamber to the spit 15 basin. These two channels guarantee an unhindered and quick discharge of the spit from the smoke chamber, so that only dry smoke is sucked by the smoker. These channels are easily cleaned and cannot possibly 20 get choked up.

The drawing shows one form of this new pipe. Fig. 1 is a section and Fig. 2 is a cross section of a cleaning pin for the smoke channel, on an enlarged scale.

30 The straight smoke channel (a) which leads from the smoke chamber (c) to the spit basin (d) cuts the bottom of the bowl in a suitable manner so that the channel will be in connection with the bowl. The spit basin (d) is preferably provided with a thread. There is a straight spit channel (b) leading from the bottom of the smoke chamber (c) to the spit chamber (d) and the spit accumulated in the smoke chamber 35 will quickly be emptied through said channel (b) into the spit chamber (d).

Owing to the fact that the spit is imme-

dately removed, the smoke will always remain completely dry.

When the spit chamber has been taken off, 45 said channels are easily cleaned in consequence of their straight form and in addition a cleaning pin (e) can be put into the smoke channel, said pin having a section as shown in Fig. 1. The grooves (r) in the pin 50 (e) will facilitate cleaning inasmuch as the edges of the pin will take off all crusts and other impurities. The grooves (r) may be spiral-shaped, as shown in Fig. 1 or they may as well be straight. This pin is pref- 55 erably fixed to the spit basin, so that, when this latter is being screwed off, said pin will turn in the smoke channel. The end of the pin projecting from said channel, may also be loose within the spit basin.

I claim:

1. In a tobacco pipe a straight smoke channel, connecting the bowl hole with a saliva chamber and a smoke chamber in the shaft discharging high above the bottom of this chamber, the saliva chamber consisting of a removable basin, a straight saliva channel connecting the saliva chamber with the bottom of the smoke chamber, the axis of both channels crossing the saliva basin and a 65 removable grooved pin in the smoke channel.

2. In a tobacco pipe a straight smoke channel connecting the bowl hole with a saliva chamber and a smoke chamber in the shaft discharging high above the bottom 75 of this chamber, the saliva chamber consisting of a removable basin, a straight saliva channel connecting the saliva chamber with the bottom of the smoke chamber, the axis of both channels crossing in the saliva basin, 80 and a spiral grooved pin in the smoke channel fastened to the saliva basin.

In testimony whereof I affix my signature.
MAX SCHIERS.
